(57) **CLAIM**

The ornamental design for a pair of motorcycle highway bars, as shown and described.

DESCRIPTION

FIG. 1 is a right, front, perspective view of a pair of motorcycle highway bars showing my new design; FIG. 2 is a right side elevation view of the right-hand bar, shown separately for ease of illustration thereof; FIG. 3 is a left side elevation view of the right-hand bar, shown separately for ease of illustration thereof; FIG. 4 is a left, rear, perspective view of the pair of motorcycle highway bars; FIG. 5 is a left side elevation of the left-hand bar, shown separately for ease of illustration thereof; FIG. 6 is a right side elevation view of the left-hand bar, shown separately for ease of illustration thereof; FIG. 7 is a front elevation view of the right-hand bar, shown separately for ease of illustration thereof; FIG. 8 is a front elevation view of the left-hand bar, shown separately for ease of illustration thereof; FIG. 9 is a rear elevation view of the left-hand bar, shown separately for ease of illustration thereof; FIG. 10 is a rear elevation view of the right-hand bar, shown separately for ease of illustration thereof; FIG. 11 is a top plan view of the left-hand bar, shown separately for ease of illustration thereof; FIG. 12 is a top plan view of the right-hand bar, shown separately for ease of illustration thereof; FIG. 13 is a bottom plan view of the left-hand bar, shown separately for ease of illustration thereof; and, FIG. 14 is a bottom plan view of the right-hand bar, shown separately for ease of illustration thereof. The broken line showing of the connector pieces is for the purpose of illustrating environmental structure and forms no part of the claimed design.

1 Claim, 8 Drawing Sheets
